RALPH GARLICK, OF TOTAWA BOROUGH, NEW JERSEY, AND HENRY SELLMAN, OF BROOKLYN, NEW YORK, ASSIGNEES TO PAUL O. ABBE INC., OF LITTLE FALLS, NEW JERSEY, A CORPORATION OF NEW JERSEY

DISCHARGE VALVE FOR BALL AND PEBBLE MILLS

Application filed November 28, 1924. Serial No. 752,638.

This invention relates to rotary ball and pebble mills and other hollow drums and containers for liquid and mixed contents, and more particularly to the discharge valves for 5 the same.

The main object of our invention is to provide a mill or drum with a discharge valve whose main moving member virtually constitutes a plug for the valve casing in closed position and tends to be retained in the closed position through action of the centrifugal force produced upon rotation of the drum involved, due to the fact that said valve member is normally arranged to project outward 10 from said drum.

Another object is to provide such a drum or mill with a valve of the indicated character which also has a positive means for retaining the valve in tightly closed position.

20 A further object is to so construct such a valve that the main moving member is conveniently and positively shifted to open position by simultaneous rotation and raising thereof into the interior of the mill involved in such manner that the contents to be discharged will assist in closing the valve by 25 gravity when it is desired to close said valve.

A still further object is to furnish such a valve with an auxiliary closing means to afford both initial and final control of the contents to be discharged through the same.

Other objects and features will appear hereinafter as this specification proceeds.

In the drawings forming part thereof, 35 Fig. 1 is a view of a rotary drum provided with a discharge valve made according to our invention and together with said drum constituting a novel and highly useful structure in the art.

40 Fig. 2 is a sectional view of the same drum revealing the position and relation of the valve thereon.

Fig. 3 is a bottom plan view of the discharge valve of the other views.

45 Fig. 4 is similar to Fig. 2, and shows the charging cover open and the discharge valve in raised position and in section to further reveal its construction.

Throughout the views, the same reference 50 numerals indicate the same or duplicate parts.

In rotary drums, especially in ball mills of large size, it is very laborious and inconvenient to remove the very large charging covers with which such mills are usually equipped. The reason for this is that the 55 openings in this kind of drums are necessarily made large enough for the passage of a workman's body, as the lining periodically requires replacing and other repairs, and this is therefore allowed to determine the size 60 of the charge openings, and, incidentally the covers for the same. The labor is increased by the fact that the workman must often remove and replace the cover in question several times a day.

65 In the practice of our invention, a hollow drum 1 is mounted on a stand 2 which supports the trunnion 8 of the drum, and an extension 10 of the stand is adapted to support a motor 9 or a similar source of motive power. 70 A hardened ring or collar 5 is keyed in the trunnion, and is a sliding fit in the bore of the worm gear 3, the latter being housed in a casing 4 on the stand. The motor is furnished with a worm 7 which meshes with the 75 gear, and the motor is therefore adapted to rotate the worm gear when in motion.

If the parts were simply made as thus far described, no movement would be transmitted to the drum 1, but the gear would 80 merely rotate about the ring 5. But in order to introduce tangible connection between the ring and the gear, the ring is provided with a series of peripheral wedge slots 6-6, in which wedging rollers may be located in 85 such manner that when the gear is revolved clockwise, at least one of the rollers is sure to be in a position to drop by gravity from the wider portion of the respective slot toward the narrower portion thereof. As soon 90 as the roller comes into intimate contact with the trunnion and the slot face a wedging action will take place, likewise, the ring itself being thus subjected to pressure against the bore of the gear on the opposite side, will 95 also bind, the two resulting in a good frictional connection between the worm gear and the trunnion, permitting the motor to directly rotate the drum.

However, when the motor is stopped, the 100

worm gear has a tendency to come to a very early stop, but the drum by virtue of its momentum will tend to keep on rotating. This will release the wedged rollers and draw them up into the wide parts of their respective slots where no effective contact or wedging of the parts is possible, with the result that the drum continues to rotate freely until its momentum is spent and it comes to a gradual stop. This also allows the drum to be partly rotated and shifted to proper charging and discharging positions.

A large charging ring 11 has been included in the construction of the apparatus and is secured to the drum by bolts as at 12—12, being of course, large enough to permit the entry of a workman into the drum when removed. But a second cover, the actual charging cover 13 is adapted to be secured in the charge opening 29 of the ring by wing nuts 14—14, and together with the ring forms a complete closure for the upper part of the drum. The small cover is comparatively light and easy to handle and involves no great labor to remove and replace when adding charges of material and liquid media to the contents of the mill. The large ring need only be removed upon such rare occasions as when actual repairs to the drum lining 27 or renewals have to be made. Even then, the preliminary removal of the small cover will materially lighten the ring and facilitate handling also of the latter. The charging cover has a filler of lining at 26 and the ring cover a lining 25 to raise the inner faces to correspond with the interior drum lining 27.

To complete the structure of the drum in a form of added utility, a discharge valve 28 is included in the lower part of the same, and comprises a threaded tube or hollow plug 16 slidable through the wall of the drum and which has a series of vertical slots 20 in its side walls and an imperforate top 24. The tube is retained in position by means of a threaded block 15 which fits the threaded portion of 16, and is preferably made sufficiently heavy to counterbalance the weight of the covers 11 and 13, and is secured to the drum by screws or by any other removable means.

If the tube should be rotated axially, it will be raised or lowered, by virtue of its threaded portion being engaged by the block, and when thus raised, the slots in the upper part of the tube will be exposed above the inner surface of the wall of the drum to whatever contents may be in the interior of the same, and will, of course, permit said contents to drain out through these slots and the tube. The upper extremity 21 of the valve casing is preferably flush with the inner surface of the drum wall so as to virtually constitute a part thereof.

The lower part of the tube is exteriorly provided with castellations 23—23 to adapt

the same for rotation by means of a spanner wrench or the like, and interiorly is provided with a sliding plate 18 by which to control intermittent discharge of material from the tube opening 19. The handle pin 17 is attached to the plate by which to move the latter, and may fit into one of the castellations in retracted and inoperative position. It is easily seen that the tube may as a whole be projected only part of the way up into the drum, or all its possible extension therein, according to the desire of the operative, and this allows of great facility in adjustment and control both of the drum, and the contents of the same.

Slight variations and modifications of our invention may be made without departing from the spirit thereof, such as omitting the sliding plate 18, should we desire to do so.

Having now fully described our invention, we claim:

1. In a rotatable drum having a discharge valve in the wall thereof, said valve including a slidable tube in said wall provided with a closed top, a perforate portion in the wall of said tube beneath said closed top and a threaded portion below said perforate portion, a threaded block upon said drum arranged to receive the threaded portion of said tube, and actuating means upon said tube for rotating the same so as to project and withdraw the tube into and from the interior of said drum in order to expose said perforate portion to the interior of the drum or to cover and close said tube with respect to said drum interior in such manner that in the projected position of said valve tube, the same will constitute a projection into said drum, and in the withdrawn position, the closed top thereof will be sunk approximately flush with the interior wall of the drum and will substantially form a part thereof.

2. A rotatable drum having a discharge valve in the peripheral wall thereof, said valve including a slidable tube having a closed top, a perforate portion in the wall of the tube and a threaded portion also disposed on said tube, there being a block on said drum wall arranged to fit said threaded portion of the tube, and projections disposed upon the exterior of said tube, whereby to axially rotate the same and thereby raise and expose said perforate portion above the inner surface of the wall of the drum in order to permit draining of fluids from said drum through said perforate tube portion and tube, the top of the tube, in closed position constituting an imperforate plug in the interior wall of said drum.

3. A discharge valve including a casing, a tube slidable through the wall of said casing and provided with a closed top, said tube also having a perforated portion in the wall thereof below said top and normally closed by the wall of said casing, means to

raise said tube and thereby expose said perforated portion above the wall of the casing, and means at the lower extremity of said tube to regulate discharging through the tube, 5 including a transversely slidable plate arranged in retracted position to close the opening of the tube, and means upon said lower tube extremity to retain said plate in contact with said extremity.

10 4. In a discharge valve, the combination with a casing, of a tubular member axially slidable through the wall thereof, an imperforate top closing one extremity of said tube, means to close the other extremity independently at will, there being a plurality 15 of apertures in said tube adapted to be exposed beyond one side of the wall of said casing when moved to project therefrom in one direction, and means to move said tube axially in either direction, at will, relative 20 to said casing.

Signed at Little Falls, Passaic County, and State of New Jersey, on this 3rd day of November, 1924.

25 RALPH GARLICK.
HENRY SELLMAN.
